CLAIM

The ornamental design for a feed port for bird feeder, as shown and described.

DESCRIPTION

FIG. 1 is an environmental front view representative of one embodiment of my new design for a feed port for bird feeder, the portions shown in dotted lines being for illustrative purposes only forming no part of the present invention; FIG. 2 is a close-up front view of my new design for a feed port for bird feeder; FIG. 3 is a rear view thereof; FIG. 4 is a right side view thereof; FIG. 5 is a left side view thereof; FIG. 6 is a top view thereof; FIG. 7 is a bottom view thereof; FIG. 8 is a front view of a second embodiment showing my new design for a feed port bird feeder; FIG. 9 is a rear view thereof; FIG. 10 is a right side view thereof; FIG. 11 is a left side view thereof; FIG. 12 is a top view thereof; and, FIG. 13 is a bottom view thereof.
